MATTRESS STAPLING MACHINE

Joseph W. Droll, Wilmette, Ill., assignor to J. W. Droll Company, Chicago, Ill., a corporation of Delaware

Application August 21, 1941, Serial No. 407,747

8 Claims. (Cl. 1-2)

The invention relates to machines for stapling strips to the spring-structures of mattresses.

One object of the invention is to provide a machine for attaching a strip of suitable material around the borders of mattresses to secure the mattress filling used on the faces of the mattresses to the spring-structure.

Another object of the invention is to provide a machine of this type which is adapted to travel around the sides, ends and corners of the mattress and which comprises means for supporting a roll of the strip in advance thereof and laying the strip into position to be stapled to the spring-structure.

Another object of the invention is to provide an improved machine for stapling the upper and lower borders of mattress padding to the spring-structure.

Other objects of the invention will appear from the detailed description.

The invention consists in the several novel features which are hereinafter set forth and are more particularly defined by claims at the conclusion hereof.

In the drawings: Fig. 1 is a side elevation of the stapling machine and a portion of the supporting table for the mattress. Fig. 2 is a plan. Fig. 3 is a perspective of the stapling device and the holder for the strip while it is being stapled to the spring-structure of the mattress. Fig. 3^a is a perspective of the staple former. Fig. 3^b is a section on line 3^b-3^b of Fig. 14. Fig. 4 is a section taken on line 4-4 of Fig. 1. Fig. 5 is a section taken on line 5-5 of Fig. 4. Fig. 6 is a section taken on line 6-6 of Fig. 4. Fig. 7 is a section taken on line 7-7 of Fig. 4. Fig. 8 is a section taken on line 8-8 of Fig. 4. Fig. 9 is a section taken on line 9-9 of Fig. 4. Fig. 10 is a plan of the device for laying the strip around the upper corner of the border of a mattress-structure, the carriage and holder for the strip being shown in section. Fig. 11 is a perspective of the device for supporting the supply for the strip. Fig. 12 is a side elevation of the stapling mechanism, parts being shown in section. Fig. 13 is a transverse section illustrating a staple being driven through the strip and filling of the mattress. Fig. 14 is a view of the stapling mechanism illustrating the former and driver in their lowered position, the front plate of the head in which the former is slidably being removed. Fig. 15 is a similar view illustrating the staple former and driver in their raised position. Fig. 16 is a

detail of the mechanism for shifting the staple-driver.

The invention is exemplified in a machine which comprises a horizontal table *a* for supporting the mattress-structure and a carriage *b* which is adapted to travel completely around the table. The carriage supports a stapling mechanism *c* and an electric motor *d* for supplying power for propelling the carriage *b* around the table and for operating the stapling mechanism.

The machine is exemplified as used for securing a strip *e* of fabric, such as muslin (Fig. 13) and filling of padding *f*² around the border-members *f*¹ of the spring-structure *f* of a mattress, by staples *g*. The staples are driven through the upper and lower portions of strip *e* and padding *f*², inwardly of the border-member *f*¹, for securing the strip and padding to and around the border-member *f*¹.

The table *a* is rectangular with rounded corners and is adapted to support the spring-structure with the padding thereon. The border of the structure will be adjacent to and conforms to the table. The stapling and strip-laying device is adapted to travel completely around the table and mattress-structure.

The carriage *b* is supported and guided around the table in a path conforming to the contour of the mattress-structure by a track *h* which extends around the table and is supported on fixed standards or legs *g*¹. The track *h* is provided with a continuous groove *h*². A pair of rollers *h*³ (Figs. 4 and 5) ride on the bottom of the groove *h*², to vertically support the carriage *b*. Rollers *h*³ are mounted in arms *15*, respectively. Arms *15* are pivotally connected to vertical pins *16* to permit them to caster around the corners of the track *h* and said pins are carried by an extension *17* of the carriage *b*. The lower portion of the carriage is held against transverse tilting by a lower roller *18* which is mounted on the lower end of carriage *b* and rides on a vertical track *19* which extends around the table and conforms to the contour of the mattress. The carriage *b* is guided laterally to travel in a path which conforms to the sides, ends and rounded corners of the mattress-border by rollers *20* and *21* which are mounted on the lower ends of studs *16* and engage the sides of the groove *h*² in track *h*. Roller *20* at the trailing side of the carriage *b* engages the lower portion of the sides of the groove *h*² in track *h* and roller *21* engages the upper portion.

The rounded corners between the sides and the ends of the track are formed in the bracket h^4 . The sides of the track-grooves h^2 in each corner bracket h^4 have straight portions 24 at the top of the track which intersect the curve h^5 in the corner. These straight portions are engaged by the upper roller 21 which is located at the leading end of the carriage to cause the carriage to move rectilinearly until the point at which the stapling is done reaches the curve at the corner of the border or the mattress. The lower portion of the sides of the track-groove in each bracket h^4 is formed with a convexly curved portion 22 on the inner side of the groove and a concavely curved portion 23 on its outer side. Curved portions 22 and 23 are engaged by the trailing roller 20 . Each bracket h^4 is also provided with a similarly convexly curved inner side portion 25 and a concavely curved outer side portion 26 which is engaged by the roller 21 . Each bracket is also provided with straight portions 27 on the lower portion of the inner and outer sides of the track-groove which are engaged by the roller 20 . This track formation for the corners causes the stapling point on the carriage to travel in an arc which conforms to the arc of the curved corners of the border of the mattress-structure where the staples are to be driven through the strip e inwardly of the border-member of the spring-structure.

The motor d , through an endless belt d^1 , drives a shaft d^2 which is suitably journaled in the carriage. A gear d^3 on shaft d^2 , drives a gear d^4 which drives a gear d^5 on a shaft d^6 . All of this gearing is mounted in the carriage b so it will travel therewith.

The mechanism for propelling the carriage b around the table and mattress-structure comprises a cam-groove 28 in gear d^5 ; a lever 29 fulcrumed at 30 in the carriage b and provided with a stud 31 which rides in the groove 28 ; a link 32 pivoted to the free end of lever 29 ; an arm 33 to which link 32 is pivoted at 33 ; a one-way ball and ratchet clutch 35 , the driven member of which is connected to a bevelled gear 36 which is operated step-by-step by the driven member of the clutch; a bevelled gear 37 meshing with gear 36 ; a clutch 38 on a vertical shaft 39 , which is adapted to drive said shaft; a gear 40 fixed to the upper end of shaft 39 and a rack 41 extending around the track h . Clutch 38 is controlled by a handle 42 which is adapted to uncouple the clutch when it is desired to keep the carriage b stationary. This exemplifies a mechanism for intermittently propelling the carriage b on the track h around the table a and the mattress-structure thereon.

The invention comprises means for automatically laying and folding the strip of fabric e , such as muslin, around the border of the padding and the border-member of the spring-structure as the carriage b which carries the stapling device is propelled around the table. This device comprises a support for a roll e^1 of fabric strip e which is supported to travel in advance of the carriage b . The strip is wound flat in the roll e^1 and extends from the mattress-structure through a shoe 43 (Figs. 3, 13 and 14) which is fixedly secured to the inner face of the frame c^1 which carries the stapling mechanism c . An anvil 44 for the stapling device is mounted on the frame c^1 adjacent the inner open side of shoe 43 .

The bottom of the shoe 43 and the anvil 44 are positioned so the lower portion of the strip e will be held to extend inwardly and downwardly from the curved outer portion 43^a of the shoe. The stapling mechanism is operated in a path at right-angles to the plane in which the lower portion of strip e is held by the anvil and shoe to drive the staple through the mattress-structure and strip e at a downwardly and outwardly extending angle. The upper member of the shoe is provided with an upwardly and inwardly inclined wall 43^b for engaging and pressing the upper portion of strip e and the padding downwardly and inwardly of the border-member f^1 while the staple is being driven. Wall 43^b is provided with an opening 43^c through which the staple is driven by the former and driver of the stapling mechanism. This shoe folds the strip around the border-member of the spring-structure, compresses the padding f^2 and forms it into a roll f^4 around the border member f^1 and draws the strip tightly around the roll of compressed padding while the staples are being driven.

Spool e^2 for the roll e^1 is held on a vertical spindle 45 which is mounted on a bracket 46 which is propelled around the mattress with and in advance of the carriage b . Bracket 46 is supported and guided by the track h . A plate 47 is fixed to bracket 46 and extends over the groove h^2 in the track (Figs. 7 and 11) and slides on the top of the track h . A roller 48 on a stud 49 engages the lower portion of the sides of the groove h^2 and a roller 50 on a stud 51 engages the upper portions of the sides of the groove h^2 of the track h . Studs $48, 51$ are mounted in plate 47 . Rollers 48 and 50 guide the bracket 46 so it will travel around the corners of the track substantially in the same path as the carriage b which carries the stapling mechanism. A screw-stud 52 (Fig. 7) carried by a bar 53 which is fixed to bracket 46 prevents the upward displacement of rollers 48 and 50 from the track h . The bracket 46 is provided at its lower end with a roller 46^a which rides on the outer side of a vertical track 19 to prevent lateral tilting of bracket 46 and the parts supported thereby.

The bracket 46 and the roll e^1 are propelled from the carriage b by a pair of push-links $54, 56$. Link 54 is pivoted to carriage b by a vertical pin 55 and to link 56 by a pin 57 . Link 56 is pivoted, at its leading end, by a pin 58 to the bracket 46 . The pivot-pin 57 , between links $54, 56$, is carried by a block 61 . A roller 59 which travels in the lower portion of the groove h^2 of the track h , is connected by a bar 60 to a block 61 which carries the pivot 57 . A lower bar 62 , fixed to block 61 , extends under the track h to prevent upward displacement of the roller 59 . This linkage propels the bracket 46 around the track h . The strip e is held against unwinding from the roll e^1 by a friction-member 64 which is fixed to pivoted arm 65 which is pressed by a spring 66 to force the member 64 against the roll e^1 . The strip is looped around pins 67 and 68 (Fig. 12) and is held by pin 68 close to the border of the mattress. The strip between the roll e^1 and the shoe 43 is under tension so that it will be kept taut for folding the strip e around the border of the mattress-structure by the shoe. As the spool e^2 is advanced away from the portion of the end of the strip e which has been stitched to the mattress-structure, the strip e will be drawn from the roll e^1 a distance equal to the advance of the carriage b . The links $54,$

56 which push the spool-supporting bracket 46 propel the spool around the round corners of the track and fold it around the corners of the mattress-structure in advance of the carriage *b*, as illustrated in Fig. 10. This exemplifies mechanism for propelling the supply-roll of strip *e* in advance of the carriage *b* and for laying or folding it against the border of the mattress-structure. As the head travels step-by-step, the strip *e* will be pulled from the roll *e*¹ and laid in place in advance of the stapling device along the sides, ends and corners of the mattress-structure. A shoe 69 is fixed to bracket 46 to deflect any portion of the padding or spring-structure out of the path of the support for the spool *e*².

The stapling mechanism is mounted on the carriage *b* so it will be propelled therewith around the mattress-supporting table *a*. This mechanism comprises a head 71 which is fixedly supported from the frame *c*¹ which is secured to the top of the carriage *b*; a former 72 slidably mounted in head 71; and a driver 73 slidably mounted in the former 72. The former 72 is composed of front and back plates which are spaced apart at their margins by bars which extend below said plates for bending the ends of the severed strip. The driver 73 is slidably mounted in grooves in said bars. The former 72 is reciprocated in head 71 by a lever 74 which is fulcrumed at 75 in the frame *c*¹ and operated by a rod 76 which is reciprocated by a cam-groove 77^a formed in one side of wheel 77 which is fixed to and driven by shaft *d*⁶. The free end of lever 74 carries a roller which slides in a yoke 83^a on the upper end of the former 72. The upper end of rod 76 is provided with a box 78 for a slidable block 79 in which is pivoted the stud 80 which connects said block to lever 74. The downward movement of rod 76 imparts the operative stroke to lever 74 and operates the former through a spring 81 interposed between the upper end of the box 78 and the block 79. This spring forms a resilient connection for operating lever 74 so that if the former should encounter the corner helical of the spring-structure of the mattress, in lieu of engaging the strip *e* inwardly thereof, the former can yield to avoid breakage of the operating mechanism or breakage of the helical.

The driver 73 is reciprocated by a lever 83 (Fig. 16) which is fulcrumed at 75 and is operatively connected to the upper end of the driver by a roller and yoke similar to the connection between lever 74 and the former 72. Lever 83 is rocked by a rod 84, the lower end of which is shifted by a lever 84^d which is operated by a suitable cam-groove 84^a in one side of wheel 77 which is fixed to the shaft *b*⁶. The upper end of rod 84 is connected to lever 83 by a resilient connection consisting of a block 80 which is pivotally connected to the lever and is slidably mounted in a box 81 and a spring 92 interposed between the top of the box and block 90. The operative stroke of rod 84 is downward and the resilient connection permits the staple-driver 73 to be arrested to prevent breakage during the operative stroke in the event that the driver strikes the border-helical or any portion of the spring-structure.

The wire *k* from which the staples are formed is drawn from a spool *k*¹ and passes through straightening rollers *k*² to a pair of feed-rollers *k*³, *k*⁴, all of which are mounted on frame *c*¹ and travel with the carriage *b*. These feed-rollers

are intermittently operated by any suitable mechanism from shaft *d*⁶ to feed a length of wire for forming a staple while the former 72 and driver 73 are in their normal or raised position. The wire 5 is fed over an abutment 86 which is slideable into and out of the path of the driver 73 by a cam 86^a on shaft *d*⁶, and a lever 86^b which is rocked by said cam and pivoted to a stem on abutment 86. The wire fed into the head 71 over abutment 86 passes between a pivoted knife 88 and a shear plate 89. The knife 88 is intermittently operated to shear the wire from the shaft *d*⁶ by a cam 88^a on the periphery of wheel 11, an arm 88^b and a lever 88^c which is pivoted to the knife. After the length of wire has been sheared off and rests on abutment 86 the former is operated downwardly to bend the ends of the strip of wire downwardly to form prongs. The abutment 86 is then withdrawn from the path 10 of the driver. The former 72 and driver 73 are next moved downwardly to drive the prongs of the staple through and to pinch the strip *e* and the padding. The strip and padding will be indented by the former 72. The staple will be driven downwardly to cause the prongs of the staples to be bent inwardly by the grooves in the anvil 44 and the strip and padding to be tightly secured around the border-member of the spring-structure. The mechanisms for feeding the wire and operating 15 the abutment 86 may be of any suitable construction well understood in the art and therefore have not been illustrated and described in greater detail.

The table *a* is provided with four depending 20 rack-bars 95 which are slidably mounted in the corner brackets *h*⁴ of the track *h*, so that the table *a* may be raised or lowered to bring the border of mattress-structures of different thickness into horizontal alignment with the shoe 43. These 25 rack-bars may be conjointly raised and lowered by interconnected shafts 96 and pinions 97 which engage the rack-bars 95, respectively, for rectilinear raising and lowering of the table *a*.

The operation of the machine is as follows: 30 the assembled spring-structure for the mattress, including the border-members *f*¹ and springs *f*, will be laid on the table *a*. The padding *f*² will be laid on top of the spring-structure with 35 its marginal portions extending over and depending from the helicals *f*¹. The free end of the strip *e* and the adjacent portion of the padding *f*² will be placed into the shoe 43. The stapling mechanism *c* will then be operated to drive a 40 staple through the upper and lower folds of the strip *e*, and the padding *f*², inwardly of the helical *f*¹ and secure them around the helical. During the stapling operation the carriage *b* will remain stationary. After a staple has been driven the 45 arm 33 which remains stationary during the stapling operation will be operated to rotate gear 40 which, by its engagement with the stationary rack 41, will propel the carriage *b* and all the mechanisms supported thereon a distance equal 50 to the desired spacing between the staples *g*. A stud and slot connection 33^a between rod 32 and arm 33 permits the stroke of said arm to be varied 55 according to the spacing desired between the staples. After the first staple has been driven 55 through the strip *e* the latter will be attached to the border of the mattress and the strip will be kept taut in shoe 43 and between the shoe and the supply-spool *e*². During the advance of the carriage *b* the spool *e* will be advanced a corresponding step by the links 54, 56 which push the 60

bracket 46, which carries said spool. This advance of the spool e^2 will cause the strip to be automatically drawn from the spool and laid around the border of the mattress-structure. At the conclusion of each step of advance of the carriage b and bracket 46 the operation of the stapling device will be repeated to secure the next staple in the mattress-structure. These operations will be repeated until the strip e has been stapled to the entire border of the mattress-structure. When the carriage b reaches a corner of the track h , it will be guided around the mattress-structure on an arc which will cause the path of the stapling mechanism to conform to the border of the mattress-structure. The supporting-bracket 46 from the spool e^2 travels around a corner of the track a considerable distance in advance of the carriage b and the stapling device c . The links 54, 56 cause the bracket 46 and spool e^2 to pass around the corner in advance of the carriage and to lay or draw the strip e snugly around the corner of the border of the mattress-structure. When the strip e has been stitched around the border on one face of the mattress-structure it will be cut off. The mattress-structure is then inverted on the table a and the strip is stapled in the same manner around the border of the other face of the mattress-structure.

The invention exemplifies a machine for stitching a strip to a mattress-structure which is adapted to travel around the border of the structure and to progressively drive staples to secure the strip to the padding and spring-structure and in which the spool from which the strip is wound travels with and in advance of the stapling device and which is adapted to automatically stitch the strip around the entire border of a mattress-structure.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a machine for assembling spring-structures having border members and padding for mattresses, the combination with a table for supporting the spring-structure and padding thereon, a track conforming to the mattress-border and extending around the table and having rounded corners between the sides and ends, a carriage supported on the track and adapted to travel around the border of the spring-structure, and mechanism for propelling the carriage along the track, of a device mounted on the carriage provided with means for folding a strip of material to lap the top and side of and to simultaneously compress the padding around the upper border-member of the spring-structure and with means extending inwardly from the first mentioned means for folding the padding under and inwardly of said border-member, an anvil supported to travel with the carriage inwardly of said border-member and under the infolded portion of the padding and positioned for receiving a staple driven through the strip and the padding, and staple-driving mechanism mounted on and to travel with the carriage and positioned to drive a staple through the strip and padding inwardly of the border-member and against the anvil for simultaneously securing the padding and the strip to the spring-structure.

2. In a machine for assembling spring-structures having border-members and padding for mattresses, the combination with a table for supporting the spring-structure and padding thereon, a track conforming to the mattress-border and extending around the table and having rounded corners between the sides and ends, a carriage supported on the track and adapted to travel around the border of the spring-structure, and mechanism for propelling the carriage along the track, of a shoe on the carriage provided with a face for folding a strip of material to lap the top and side of and to simultaneously compress the padding around the upper border-member of the spring-structure and with a face extending inwardly from the first mentioned face for folding the padding under and inwardly of said border-member, an anvil supported to travel with the carriage inwardly of said border-member and under the infolded portion of the padding and positioned for receiving a staple driven through the strip and the padding, and staple-driving mechanism mounted on and to travel with the carriage and positioned to drive a staple through the strip and padding inwardly of the border-member and against the anvil for simultaneously securing the padding and the strip to the spring-structure.

3. In a machine for assembling spring-structures having border members and padding for mattresses, the combination with a table for supporting the spring-structure and padding thereon, a track conforming to the mattress-border and extending around the table and having rounded corners between the sides and ends, a carriage supported on the track and adapted to travel around the border of the spring-structure, and mechanism for propelling the carriage along the track, of a shoe on the carriage provided with upper and lower inwardly extending faces and a curved connecting face between said upper and lower faces, said upper face and a portion of the connecting face being adapted to fold a strip of material to lap the top and side of and to simultaneously compress the padding around the upper border-member of the spring-structure, said lower face extending inwardly from the curved face and adapted to fold a portion of the strip and the padding under and inwardly of said border member, an anvil supported to travel with the carriage inwardly of said border-member and under the infolded portion of the padding and positioned for receiving a staple driven through the strip and the padding, and staple-driving mechanism mounted on and to travel with the carriage and positioned to drive a staple through the strip and padding inwardly of the border-member and against the anvil for simultaneously securing the padding and the strip to the spring-structure.

4. The combination with a machine comprising a table for supporting a spring-structure for a mattress having border-members and padding thereon, a track conforming to the mattress-border, extending around the sides and ends of the table and having rounded corners between the sides and ends, a carriage supported on the track and adapted to travel around the border of the spring-structure, mechanism for propelling the carriage along the track, of stapling mechanism mounted on and to travel with the carriage, a shoe on the carriage comprising top and lower members for compressing the padding around the border-member of the spring-structure and folding a strip around the compressed padding, means for operating the stapling mechanism to drive a staple through the folded strip and padding in-

wardly of the border-member, the top member having an opening therein through which the staple is driven.

5. In a machine for assembling spring-structures having border-members and padding for mattresses, the combination with a table for supporting the spring-structure and padding thereon, a track conforming to the mattress-border and extending around the table and having rounded corners between the sides and ends, a carriage supported on the track and adapted to travel around the border of the spring-structure, and mechanism for propelling the carriage along the track, of means on the carriage for forming the padding into a roll around the upper border-member of the spring-structure and folding a strip around the roll, means for laying the strip around the mattress-border in advance of the roll-forming and folding means, said laying means being adapted to travel around the corners of the track in advance of the carriage and sufficiently in advance of the folding-means to lay the strip around a corner of the mattress while the folding means is traveling rectilinearly, means for advancing the laying-means with the carriage, and mechanism mounted on and traveling with the carriage for driving a staple through the strip and the padding inwardly of the border-member of the spring-structure and for securing the folded strip and the roll around the border-member.

6. The combination with a machine comprising a table for supporting a spring-structure for a mattress having border-members and padding thereon, a track conforming to the mattress-border, extending around the sides and ends of the table and having rounded corners between the sides and ends, a carriage supported on the track and adapted to travel around the border of the spring-structure, mechanism for propelling the carriage along the track, of stapling mechanism mounted on and to travel with the carriage, means mounted on the carriage for holding a strip of material around the border of the mattress-structure, means for operating the stapling device to drive a staple through the strip inwardly of the border-member, a bracket for supporting a portion of the strip to travel around the corners of the table in advance of the carriage, means for guiding the bracket by the track to travel around the table, and a pair of pivotally

connected links connected to, and in advance of, the carriage for shifting the bracket around the table.

7. The combination with a machine comprising a table for supporting a spring-structure for a mattress having border-members and padding thereon, a track conforming to the mattress-border, extending around the sides and ends of the table and having rounded corners between the sides and ends, a carriage supported on the track and adapted to travel around the border of the spring-structure, mechanism for propelling the carriage along the track, of stapling mechanism mounted on and to travel with the carriage, means mounted on the carriage for folding a strip around the border of the mattress, means for operating the stapling device to drive a staple through the strip of padding inwardly of the border-member, a bracket for supporting a roll of the strip to travel around the corners of the table in advance of the carriage, means for guiding the bracket by the track to travel around the table, and a pair of links connected to each other by a pivot and connected to, and in advance of, the carriage for shifting the bracket around the table, and means for guiding the pivot between the links by the track.

8. The combination with a machine comprising a table for supporting a spring-structure for a mattress having border-members and a padding thereon, a track conforming to the mattress-border, extending around the sides and ends of the table and having rounded corners between the sides and ends, a carriage supported on the track and adapted to travel around the border of the spring-structure, mechanism for propelling the carriage along the track, of stapling mechanism mounted on and to travel with the carriage, means on the carriage for folding a strip of material around the border-member of a mattress-structure, means for operating the stapling mechanism to drive a staple through the folded strip, a support for a roll of the strip mounted to travel on and around the corners of the track in advance of the carriage for laying the strip along the mattress-structure in advance of the folding means, and a link-connection between the carriage and the support whereby the strip will be laid around a corner of the mattress-structure before the carriage reaches the corner.

JOSEPH W. DROLL.
